Filed June 12, 1958, Ser. No. 741,482

2 Claims. (Cl. 204—244)

This invention relates in general to electrolytic cells for the production of aluminum. More particularly, the invention relates to a new and improved wall and cathodic current conducting element structure for electrolytic cells for the production of aluminum.

This application is a continuation-in-part of application Serial No. 549,347, filed November 28, 1955, now Patent No. 2,915,442.

The use of refractory hard metal negative current conducting elements, i.e., cathodic elements, in aluminum reduction cells has been previously disclosed in the art, e.g., French Patent 1,064,743. This French patent discloses three arrangements of refractory hard metal cathodic current-conducting elements for use in aluminum reduction cells. These three arrangements are (1) horizontal side entering wherein the refractory hard metal elements extend horizontally through the vertical side walls of the reduction cell and project at their interior extremities into the molten aluminum layer, (2) top entering refractory hard metal elements wherein the elements are disposed along the sides of the cavity or chamber of the cell and pass through the solidified crust and molten electrolyte and terminate at their extremities a short distance above the base of the cell, and (3) the refractory hard metal current-conducting elements are disposed vertically and introduced into the molten metal layer through the base of the electrolytic cell.

As used herein in the specification and the claims, the expression "refractory hard metals" refers to a material which possesses a low electrical resistivity, a low solubility in molten aluminum and molten electrolyte under cell operating conditions, is wettable by molten aluminum under cell operating conditions, and has a good stability under conditions existing at the cathode of a reduction cell. The preferred refractory hard metal material for at least that portion of such element in contact with the molten aluminum consists essentially of at least one of the materials selected from the group consisting of the carbides and borides of titanium, zirconium, tantalum and niobium and mixtures thereof, such materials being found to exhibit all or substantially all of the above properties.

The expression "consists essentially," as used herein-after in the specification and the claims, means that the refractory hard metal material of the carbides and borides referred to above does not contain other substances in amounts sufficient to materially affect the desirable characteristics of the material, although other substances may be present in minor amounts which do not materially affect such desirable characteristics, for example, small proportions of oxygen, nitrogen and iron in titanium boride.

Because these refractory hard metals are inherently expensive, one of the major problems in designing reduction cells employing refractory hard metal current conducting elements is that of being able to utilize the minimum possible amount of the refractory hard metal material and still accomplish the maximum advantages of using these materials as cathodic elements. Also, the inherent fragility of these refractory hard metal materials poses a problem in furnace design. The furnace design should be such that the refractory hard metal elements are subjected to the minimum amount of mechanical stress caused by distortions in the furnace lining structure and in the furnace operation. A still further problem is that

2

of installing refractory hard metal current-conducting elements in existing plants with the minimum of alteration to the furnace shells and cathode bus arrangements.

The problems have not been solved in the prior art.

- 5 In the side and bottom entering designs discussed as (1) and (3), above, relatively long pieces of refractory hard metal material are required because of the thick carbon plus insulation side and bottom lining necessary in conventional reduction furnaces to contain the molten cryolite bath and aluminum. It is possible in these two arrangements, in order to shorten the length of refractory hard metal material, to join (either by welding or bolting) the refractory hard metal element to another metal within the lining structure of the furnace. However, this has many obvious disadvantages because the joint between the refractory hard metal element and the other metal occurs within a high temperature zone. With top entering vertical leads, arrangement No. (2) discussed above, there is the serious disadvantage that the leads may be placed in locations where they would seriously interfere with normal alumina feeding, metal removal and other operations required in operating the reduction cells. In the case of existing reduction furnaces this arrangement would also necessitate, in common with the bottom entering arrangement, expensive alteration in the cathode bus.

Therefore, it is the primary object of this invention to provide a wall and refractory hard metal current-conducting elements arrangement and structure for aluminum reduction cells that overcomes or substantially reduces the disadvantages that are inherent in the prior art arrangements and structures.

It is also an object of this invention to provide a wall and refractory hard metal current-conducting elements arrangement and structure for an aluminum reduction cell wherein the elements are relatively short in length and are subjected to a minimum amount of stress.

It is a further object of this invention to provide a wall and refractory hard metal current-conducting elements structure and arrangement which is readily adaptable, without expensive alteration, to existing aluminum reduction furnaces and cathode bus.

It is also an object of the invention to provide a wall and refractory hard metal current-conducting elements structure and arrangement which permits a plurality of cells, connected electrically in series, to be arranged in side-by-side relationship, each cell being in close proximity to adjacent cells.

Other objects and advantages of the invention will become more apparent from the ensuing description and accompanying drawings.

The invention generally comprises the combination, in an electrolytic cell construction, of a silicon carbide refractory wall and horizontal refractory hard metal cathodic current conducting elements. The silicon carbide refractory wall has unique properties which make it an ideal wall material for electrolytic reduction cells. Its high thermal conductivity coupled with relatively low electrical conductivity makes possible a much thinner wall than is possible when using the conventional carbon lining. This combination makes possible the use of short lengths of refractory hard metal material for the current conducting elements and makes it possible to extend the refractory hard metal current conducting element out of the electrolytic cell where suitable connections with aluminum or other metals can be made in a cooler temperature region. With practice of the invention, the length of the refractory hard metal current conducting elements will be short enough that the elements may be fabricated in one hot pressing operation thereby obtaining elements with optimum properties at the lowest cost. Further, this combination of refrac-

tory hard metal current conducting elements and silicon carbide wall provides the shortest possible current path from the molten aluminum pool or layer to the cathode bus, and the arrangement can be adapted to both pre-bake and Soderberg reduction cells without substantial alteration in furnace shell or cathode bus system.

The expression "silicon carbide," as used in the specification and claims, refers to material wherein the grains or particles of silicon carbide are bonded by means of clays to form ceramic bonded shapes and also to material wherein the grains are bonded by means of silicon nitride derived from silicon or silicon alloys fired under proper conditions so as to react with constituents of the ambient atmosphere to form refractory nitride bonds. The silicon carbide refractory bonded by clays is commonly referred to as silicate bonded silicon carbide and is sold under the trade names of Carbofrax and Crystolon. Silicate bonded silicon carbide is attacked by molten aluminum and molten electrolyte. However, satisfactory service can be obtained from this refractory material in an aluminum reduction cell if the cell is designed and operated in order that a protective layer of frozen electrolyte, commonly referred to as ledge, forms on the silicon carbide wall areas exposed to the electrolyte and molten aluminum. The silicon carbide refractory which is bonded by silicon nitride is commonly referred to as nitride bonded silicon carbide and is sold under the trade names of Refrax and Crystolon N. The nitride bonded silicon carbide refractory is superior in its resistance to attack by aluminum and electrolyte at the elevated temperatures encountered in reduction cell operations. However, under cell operating conditions it is preferable to also protect the nitride bonded refractory with the ledge formation. However, the ledge formation in this instance does not have to be as thick as that required to afford adequate protection to the silicate bonded silicon carbide. Operating the cell with the ledge formation not only results in longer life of the refractory but also gives better purity aluminum metal, that is, the ledge formation prevents silicon from contaminating the aluminum metal. A particularly advantageous wall structure, combining the superior resistance of nitride bonded silicon carbide to molten aluminum and the low cost of silicate bonded silicon carbide, is one wherein the portions of the wall adjacent to the molten aluminum are of nitride bonded silicon carbide while the portions adjacent to the molten electrolyte are of silicate bonded silicon carbide.

In the accompany drawings are illustrated several preferred embodiments of the instant invention as applied to aluminum reduction cells.

In the drawings:

FIGURE 1 is a tranverse vertical view partly in section of an electrolytic cell which is suitable for carrying out the invention and showing same applied to the side walls of the cell;

FIGURE 2 is a transverse vertical view partly in section of a modification of the electrolytic cell shown in FIGURE 1;

FIGURE 3 is a longitudinal vertical view partly in section of an electrolytic cell showing the application of the invention to the end walls of the cell;

FIGURE 4 is a diagrammatic plan view showing an arrangement of a plurality of electrolytic cells as taught by the invention;

FIGURE 5 is a fragmentary view in section of an alternative wall and refractory hard metal current conducting elements structure.

FIGURE 1, which is a tranverse vertical view partly in section of an elongated aluminum reduction cell suitable for practice of the invention, shows an electrolytic reduction cell 10 generally comprising a metal shell 11, e.g., of steel, within which is disposed an insulating lining 12 which can be any desired insulating material, such as alumina, bauxite, clay, or aluminum silicate bricks. Within the insulating lining 12 is disposed, along the

vertical walls of the reduction cell 10, refractory walls 14 of silicon carbide brick. Deck plate 15 is positioned at the top portion of walls 14 and is suitably joined to shell 11. Within the insulating lining 12, at the bottom 5 of said cell 10, is disposed a floor 16 which can be of any desired refractory material, for instance, carbon, alumina, fused alumina, silicon carbide, silicon nitride, or other desired material. Within the chamber or cavity defined by silicon carbide walls 14 and floor 16, at the base or bottom thereof, is a pool or body 17 of molten aluminum metal. Also disposed within the chamber and in contact with the aluminum metal pool 17 is a body 18 of molten electrolyte, e.g., cryolite. Disposed at least 10 partially within the chamber and partially immersed in electrolyte layer 18 are carbon anodes 19. Anodes 19 are depicted in FIGURE 1 as being prebaked anodes; however, either prebaked or the self baking anodes known to the art may be employed in the invention. Anodes 19 are connected by suitable means (not shown) to the 15 positive pole of a source of electrolyzing current.

Molten electrolyte 18 is covered by a crust 24 which consists essentially of frozen electrolyte constituents and additional alumina. Ledge 25, which is an extension of crust 24, consists of frozen electrolyte constituents and 20 provides protection to the refractory of walls 14 from attack by molten aluminum and molten electrolyte.

Within the silicon carbide walls 14, lining 12 and shell 11, there are provided apertures (any desired number thereof) which lead into the interior of the cell adjacent the bottom of the chamber defined by silicon carbide walls 14 and refractory floor 16. Refractory hard metal current conducting elements 20 are disposed within these apertures and extend into the molten aluminum layer 17, and they also extend exteriorly of shell 11 and are 25 connected to cathodic bus bars (not shown) by means of terminal cap members 21 (which may be joined to the elements 20 in any suitable manner) and flexible metal members 22. A suitable sealing material may be packed around elements 20 within the apertures to seal 30 off the apertures and prevent leakage of the molten aluminum and electrolyte. Any suitable sealing material may be employed, for example, a carbonaceous paste which cokes upon heating. However, if no sealing material is used, the bath will flow into the apertures 35 around the elements and will freeze there and effectively seal these openings.

The apertures in steel shell 11 are preferably sufficiently large so that the steel shell does not contact the elements 20 or terminal caps 21. This prevents mechanical 40 damage to elements 20 or terminal caps 21 by a possible shifting of the refractory walls and also prevents the steel shell from becoming cathodic.

FIGURE 2, which is a transverse vertical view partly in section of an elongated aluminum reduction cell, illustrates another embodiment of the invention. In FIG. 2 there is shown an electrolytic reduction cell 30 generally comprising a metal shell 31, e.g., of steel, within which is disposed, at the bottom thereof, an insulating layer 32 which can be of any desired material, for example, alumina, bauxite, clay or aluminum silicate bricks. A castable refractory base member 33 of a suitable refractory material, such as calcium aluminate, is disposed around the bottom inner periphery of shell 31. The side and end walls 34 of electrolytic cell 30 are comprised of silicon carbide bricks. Walls 34 are supported by base member 33, and deck plate 35 is positioned at the top portion of the side and end walls 34 and is in turn suitably joined to the shell 31. Side and end walls 34 of silicon carbide brick are contiguous with shell 31, which permits wall 34 to be relatively thinner than the embodiment shown 45 in FIGURE 1, thereby permitting use of relatively shorter refractory hard metal current conducting elements, for example, on the order of 7 or 8 inches in length. Also, without the layer of insulation, the wall structure shown 50 in FIGURE 2 is better able to dissipate heat which is im-

portant in the large electrolytic cells presently employed.

The embodiments herein disclosed wherein the silicon carbide refractory is contiguous with the metal shell are particularly preferred for the large commercial electrolytic cells conventionally used in the aluminum industry.

A floor 36 of a suitable material, such as carbon, alumina, fused alumina, silicon carbide, or other desired material, is disposed on insulation layer 32. Floor 36 and walls 34 define a chamber within which is disposed, at the bottom thereof, a pool 37 of molten aluminum. Within the chamber and disposed above aluminum layer 37, and in contact therewith, is a body of molten electrolyte 38. Anodes 39 are shown as of the conventional pre-bake type; however, either pre-bake or the self-baking anode (Soderberg anode) may be employed in the invention.

Molten electrolyte 38 is covered by a crust 44. Ledge 45, which is an extension of crust 44, is disposed along the walls 34 and provides protection to the refractory of the walls 34.

As shown in FIG. 2, current conducting elements 40 project through the silicon carbide side walls 34 and shell 31 into the layer of molten aluminum 37. Each current conducting element 40 has one extremity thereof projecting into the layer of aluminum 37 and is spaced above the floor member 36. The other extremity of current conducting element 40 is suitably joined to a terminal cap member 41 of a suitable metal of high electrical conductivity, such as aluminum. Terminal cap members 41 are suitably joined to flexible metallic connectors 42 which in turn are connected to cathodic bus bars (not shown).

FIGURE 3 is a longitudinal vertical view partly in section of an aluminum reduction cell wherein the refractory hard metal current conducting elements are disposed in the end walls of the cell. In FIG. 3 there is shown an electrolytic reduction cell 50 generally comprising a metal shell 51, e.g., of steel, within which is disposed at the bottom thereof an insulating layer 52 which can be of any desired material, for example, alumina, bauxite, clay, or aluminum silicate bricks. A base member 53 of a suitable refractory material, such as calcium aluminate, is disposed around the bottom inner periphery of shell 51. The side and end walls 54 of cell 50 are comprised of silicon carbide bricks. Walls 54 are supported by base member 53, and deck plate 55 is positioned at the top portion of the side and end walls 54 and is in turn suitably joined to the shell 51. Walls 54 of silicon carbide brick are contiguous with shell 51.

A floor 56 of a suitable material, such as carbon, alumina, fused alumina, silicon carbide, or other desired material, is disposed on insulation layer 52. Floor 56 and walls 54 define a chamber within which is disposed at the bottom thereof a pool 57 of molten aluminum. Within the chamber and disposed above pool 57, and in contact therewith, is a body of molten electrolyte 58. The anodes 59 are shown as of the pre-bake type; however, either pre-bake or the self-baking anode (Soderberg anode) may be employed in the invention.

Molten electrolyte 58 is covered by crust 64. Ledge 65, which is an extension of crust 64 is disposed along the walls 54 and provides protection to the refractory of the walls 54.

Current conducting elements 60 project through the silicon carbide end walls 54 and shell 51 into the layer of molten aluminum 57. Each current conducting element 60 has one extremity thereof projecting into the layer of molten aluminum 57 and is spaced above the floor member 56. The other extremity of the current conducting element 60 is suitably joined to a terminal cap member 61 of a suitable metal of high electrical conductivity, such as aluminum. Terminal cap members 41 are suitably joined to flexible metallic connectors 62 which in turn are joined to cathodic bus bars (not shown).

The arrangement of the refractory hard metal current

conducting elements in the end walls of the electrolytic cell, as shown in FIGURE 3, has certain advantages wherein a plurality of elongated electrolytic reduction cells are arranged in side by side relationship in a pot-line.

The invention as applied to a plurality of electrolytic cells arranged in side by side relationship is shown in FIGURE 4, wherein is shown schematically a plurality of elongated electrolytic cells 90, connected electrically in series and arranged in relatively close side by side relationship. Current conducting elements 100 which are disposed in the silicon carbide end walls of cells 90, are connected to adjacent cathodic bus bars 110 in the same manner as shown for the embodiment depicted in FIGURE 3. In FIGURE 4 pre-bake anodes 99 are shown; however, as has been stated previously, the Soderberg anodes may also be used in the invention. Electrolyzing current is supplied to anodes 99 by bus bars 102 and parallel bus bars 101 leading to each row of anodes.

The arrangement of a plurality of cells depicted in FIGURE 4 greatly reduces the amount of cathode bus required and also places the refractory hard metal current conducting elements in a position where they are less subject to mechanical abuse through normal cell operating practices. Furthermore, this arrangement places the joints between the refractory hard metal elements and terminal cap members at the ends of the cells, thereby rendering the joints more accessible to repair and maintenance. In addition, the joint temperature would be much lower in this arrangement than would be the case if the refractory hard metal elements were disposed in the side walls of the cells.

FIGURE 5, which is a fragmentary vertical view partly in section of a wall and refractory hard metal current conducting elements structure, depicts the use of both silicate bonded silicon carbide and nitride bonded silicon carbide for the refractory walls of an electrolytic cell. FIGURE 5 shows an electrolytic cell 70 comprising a metal shell 71, e.g., of steel, within which is disposed at the bottom thereof an insulating layer 72 which can be of any desired material, for example, alumina, bauxite, clay, or aluminum silicate bricks. A base member 73 of a suitable refractory material, such as calcium aluminate, is disposed around the bottom inner periphery of shell 71. The wall 74 of cell 70 is comprised of portion 74a which is of silicate bonded silicon carbide bricks and portion 74b which is of nitride bonded silicon carbide bricks. Wall 74 is supported by base member 73, and deck plate 75 is positioned at the top portion of the wall 74 and is in turn suitably joined to the shell 71. Walls 74 are contiguous with shell 71.

A floor member 76 of a suitable material, such as carbon, alumina, fused alumina, silicon carbide, or other desired material, is disposed on the insulation layer 72. Floor member 76 and walls 74 define a chamber within which is disposed at the bottom thereof a pool or layer 77 of aluminum. Within the chamber and disposed above the aluminum pool 77, and in contact therewith, is a body of molten electrolyte 78. Molten electrolyte 78 is covered by crust 84. Ledge 85, which is an extension of crust 84, is disposed along the walls 74 and provides protection to the refractory of the walls 74.

Current conducting elements 80 project through the wall 74 and shell 71 into the pool of molten aluminum 77. Each current conducting element has one extremity thereof projecting into the pool of aluminum 77 and is spaced above the floor member 76. The other extremity of current conducting element 80 is suitably joined to a terminal cap member 81 of a suitable metal of high electrical conductivity, such as aluminum. Cap members 81 are suitably joined to flexible metallic conductors 82, which in turn are joined to cathodic bus bars (not shown).

In the wall structure depicted in FIGURE 5, nitride bonded silicon carbide brick of wall portion 74b is adjacent molten aluminum pool 77 and extends a distance above the top surface of pool 77. Wall portion 74a,

which is above the top surface of the aluminum pool 77 and is adjacent electrolyte 78, is comprised of silicate bonded silicon carbide bricks. The lower portion of wall 74, that is, the portion which is below the level of molten aluminum pool 77, may be of nitride bonded silicon carbide brick. However, from a cost standpoint these bricks may be of the silicate bonded silicon carbide type as is shown in FIGURE 5.

The structure shown in FIGURE 5 is advantageous in that it combines the superior resistance of the nitride bonded silicon carbide to attack by molten aluminum, while still maintaining a more economical wall structure than if the walls were composed entirely of nitride bonded silicon carbide brick.

Various changes and modifications of the instant invention may be made without departing from the principles and spirit of the invention.

What is claimed is:

1. An electrolytic cell for the production of aluminum comprising
  - A. walls of silicon carbide,
  - B. a bottom floor of refractory material,
    - (1) said walls and floor defining a chamber adapted to contain a molten aluminum pool in the lower portion of said chamber and a body of molten electrolyte in said chamber above said molten aluminum pool and in contact therewith,
    - (2) the portion of said walls adapted to be adjacent to the molten aluminum pool being comprised of nitride bonded silicon carbide and the portion above the aluminum pool and adapted to be adjacent to the molten electrolyte being comprised of silicate bonded silicon carbide,
  - C. at least one anode member disposed at least partially within said chamber and adapted to be partially immersed in said electrolyte,
  - D. at least one cathodic current conducting element spaced above said floor extending through one of said walls and having one extremity extending outside the electrolytic cell connected to a cathodic bus system and one extremity projecting through said nitride bonded silicon carbide of said wall and adapted to extend into said pool of molten aluminum,
  - (1) at least that portion of the surface of said current conducting element consisting essentially of at least one of the materials from the group consisting of the carbides and borides of titanium, zirconium, tantalum and niobium.
2. A plurality of elongated electrolytic cells for the production of aluminum, said cells being connected electrically in series and being arranged in side by side re-

lationship with the side walls of adjacent cells being in close proximity, each cell being comprised of

- A. a metal shell,
- B. side and end walls of silicon carbide refractory disposed within said shell,
  - (1) said side walls being relatively longer than said end walls,
  - (2) said silicon carbide refractory of said side and end walls being contiguous with said shell,
- C. a bottom floor of refractory material,
  - (1) said side and end walls and said floor defining an elongated chamber adapted to contain a molten aluminum pool in the lower portion of said chamber and a body of molten electrolyte in said chamber above said molten pool and in contact therewith
  - (2) the portion of said side and end walls adapted to be adjacent to the molten aluminum pool being comprised of nitride bonded silicon carbide and the portion above the molten aluminum pool and adapted to be adjacent to the molten electrolyte being comprised of silicate bonded silicon carbide,
- D. at least one anode member disposed at least partially within said chamber and adapted to be partially immersed in said electrolyte,
- E. current conducting elements projecting through said nitride bonded silicon carbide of said end walls,
  - (1) each of said current conducting elements extending through at least one of said walls and having one extremity extending exteriorly of said shell of said electrolytic cell connected to a cathodic bus system and one extremity adapted to project into said pool of molten aluminum,
  - (2) at least that portion of the surface of said element to be in contact with molten aluminum consisting essentially of at least one of the materials selected from the group consisting of the carbides and borides of titanium, zirconium, tantalum and niobium.
